VANITY CASE

Leo Esterow and Abraham Klein,
New York, N. Y.

Application December 9, 1937, Serial No. 178,904

9 Claims. (Cl. 132—79)

This invention relates to vanity cases and similar receptacles and has for its object the provision of a case of this character wherein powder, toilet articles and the like may be conveniently and safely carried; in which a slide fastener is utilized as closure means for the case; in which novel means is utilized for securing the fastener in position, and in which an improved assembly of co-operating elements is employed to provide an extremely satisfactory vanity case.

A further object of the invention is to provide a case of this character in which closure of the case is effected by means of a slide fastener secured to relatively rigid metal upper and lower case members, the invention including novel means by which the tapes of the slide fastener are secured to the case members as well as also including means by which the elements co-operating in the formation of the case members are connected together.

Another object of the invention is to provide a case of the character described having its sections or halves united by a slide fastener and having a hinge for said sections located at the periphery of the sections whereby the sections are self-supporting when the case is in its open position, and convenience in the use of the case is thus afforded.

In the accompanying drawing wherein an embodiment of the invention is shown, Fig. 1 is a plan view of a vanity case made in accordance with our invention; Fig. 2 is a transverse sectional view of the same; Fig. 3 is an enlarged sectional view of a part of the case; Fig. 4 is a rear edge view of the case; and Fig. 5 is a side elevation of the case in open position.

The body of the case consists of two main sections hinged together at 23. Section indicated at 1 constitutes the base member and that shown at 2 is the cover. Base member 1 as well as cover member 2 has a body portion composed of a slightly dished disc-shaped plate 3 having its peripheral edge portion continuously channelled as indicated at 4. Resting on top of the marginal edge portion of the plate 3 is an annulus or ring 5 which has its central opening normally closed by a hinged cover plate 6, said plate being hinged to the annulus 5 as indicated at 7 in Fig. 3, and dished slightly to hold a powder puff 25a. The dished plate 3 and the annulus 5 cooperate in the formation of a receptacle for holding powder or the like, the opening for such receptacle being normally closed by the hinged cover plate 6.

The outer face of the disc or plate 1 may be covered with suitable flexible material such as

leather, textile fabric or the like, the covering being shown at 8. Said flexible covering material is held in place on the outer face of the plate or disc 1 by having its edge portion 9 disposed in the channel 4 of plate 1 and held therein by means of a channel-shaped annular retaining strip 11. Said strip extends completely around the edge of plate 1 and has its inner side flange 10 extending into the channel 4 and engaging against the edge portion 9 of the covering 8 located in said channel and holding the edge of the covering in the channel. Said channel-shaped retaining strip 11 has an outer flange 12, which has its free edge portion 13 bent inwardly as shown in Figs. 2 and 3 to extend over the annular flange 14 on the annulus 5.

Clamped between the flange 14 of annulus 5 and the edge of the plate 3 is a tape 15 on which slide fastener elements 16 are mounted. Thus, the channel-shaped retaining member 11 operates to hold said tape 15 in position as well as to hold annulus 5, plate 3 and outer covering 8 together as a unit.

The cover member 2 is constructed similarly to the base member except that instead of being provided with the annulus 5, said cover member is provided with an inner plate member 17 recessed or depressed to receive a mirror 18. The cover member 2 is provided with a channel member 11a corresponding to that shown at 11 and 30 confining a fastener tape 19 in a manner similar to that described with respect to the maintenance of the tape 15 in position. Tape 19 carries fastener elements 20 which co-operate with those indicated at 16 to form a closure means between 35 the cover member 2 and the base section 1 of the case.

The cover member 2 and base section 1 are hinged together at their peripheries. This hinge connection is provided by means of the lug portion 21 extending upwardly from flange 11 and the co-operating lug portion 22 formed integral with and extending downwardly from the retaining strip 11a. Lugs 21 and 22 are rolled in the conventional manner to receive the hinge pin 23 and thus pivotally unite base section 1 and cover member 2.

Through the arrangement disclosed it will be noted that the hinged connection between base section 1 and cover member 2 is disposed at the periphery of the members 1 and 2 and that the slide fastener which connects the base member 1 and cover member 2 extends from one end 25 of the hinge to the other end 26, so that when the slide fastener is fully opened by means of 55

the conventional operating member 21, as shown in Fig. 5, the cover member 2 may be lifted and will incline backwardly sufficiently to enable it to retain itself in open position by its own weight, 5 as clearly shown in Fig. 5, without being supported or held in such position.

While I have shown the case or receptacle of circular or disc formation, it will be obvious that it may be made in various shapes. It will also 10 be obvious that the outer surfaces of the discs or plates comprising the body portions of the base section and a cover member may be enamelled or otherwise ornamented, thus eliminating the flexible covering 8, and various other modifications 15 may be made without departing from the spirit of the invention. The plates or discs forming the body portions of the case are relatively rigid and provide a sturdy case which holds its shape under severe conditions of use.

20 What we claim is:

1. A vanity case comprising a base section and a cover member hinged to the base section, said cover member and base section each including a relatively flat plate, a slide fastener extending 25 around the edges of the plates and comprising a closure means between the plates, said slide fastener including tapes on which fastener elements are mounted, one of said tapes being secured to each of the plates, and a channel-shaped retaining member extending around the edge of each of the plates and holding the tape in position.

2. A vanity case comprising a base section and a cover member hinged to the base section, said cover member and base section each including a 30 body portion in the form of a metal disc, the hinged connection between said discs being located at the periphery of each disc, a slide fastener extending around the edges of said discs and constituting a closure means between the 35 cover member and base section, said slide fastener including tapes on which fastener elements are mounted, and means enclosing the edge of each of the discs and clamping the edge portion of one of the tapes against said disc.

40 3. In a vanity case or like receptacle, a base member and a cover member of similar shape hinged to the base member, the edge of each of said members being provided with a continuous channel-shaped edge reinforcement, each of said 45 channel-shaped reinforcements clamping a slide fastener tape between it and the edge of the member engaged by it.

4. In a vanity case or similar receptacle, a base member and a cover member hinged together, 50 each of said members having its edge enclosed by a channel-shaped reinforcing member, a slide fastener tape having an edge portion disposed between said channel-shaped member and the edge of the cover or base member enclosed by 55 it, an inner face portion disposed on the inner side of the cover and base member respectively, said face portion having a flange at its edge, and an indent flange on the channel-shaped member

for holding the flange on the face portion, the slide fastener tape and the cover or base member edge together in clamped relationship.

5. In a vanity case, a plate member comprising a body portion for a base section or cover member, a covering disposed over the outer face of said plate member, an annular recess disposed at the peripheral edge of the plate member into which the edge portion of the covering is located, a channel-shaped reinforcement extending about the edge of the plate member and having a flange extending into the recess in the plate member and clamping the edge of the covering therein, a slide fastener tape having an edge portion located between the channel-shaped reinforcement and the edge of the plate, and a bent-over flange on the channel-shaped reinforcement for clamping the edge portion of said fastener tape between it and the edge of the plate member. 10 15 20

6. In a vanity case or similar receptacle, a pair of discs having tapes carrying slide fastener elements extending laterally from the edges of said discs and toward one another, and annular members extending around the edges of said discs and clamping the tapes between them and the edges 25 of the discs.

7. In a vanity case assembly, a plate constituting the body portion of the case, said plate having a channelled marginal edge, an annulus resting upon said channelled edge and co-operating with the inner face of the plate in the formation of a powder-containing chamber, a channel-shaped edge-reinforcement extending over the channelled edge of the plate and over the peripheral edge portion of the annulus, a slide fastener tape having a portion disposed between the edges of the plate and annulus and the reinforcement, and a bent flange on the reinforcement for clamping said tape portion between it and the said 40 edges of the plate and annulus. 30 35 40

8. In a vanity case assembly, a plate constituting the body portion of the case, an inner face member resting upon and co-operating with said plate in the formation of a case section, a channel-shaped reinforcement extending over the edges of the plate and face member and clamping said members together at their edges, and a slide fastener tape clamped against the edges of the plate and face member by the channel-shaped reinforcement. 45 50 55

9. A vanity case comprising a base section and a cover member, each of said members having a channelled reinforcement extending around the edge of the same, said reinforcements having co-operating portions forming a hinge connection between the base section and the cover member at the peripheries of the same, and slide fastener tapes held at the peripheries of the cover member and base section by said reinforcements. 60
